CLAIM

The ornamental design for an automotive visor as shown and described.

DESCRIPTION

FIG. 1 is a perspective view of an automotive visor according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in even broken line form no part of the claimed design.

Dash-dot-dash broken lines adjacent un-shaded areas represent bounds of the claimed design and form no part of the claimed design themselves.

Portions of the design shaded with stippling contrast in appearance with areas shaded with lined shading.

Diagonal shading is used to represent a reflective appearance.
